UNITED STATES PATENT OFFICE.

ANTHONY J. METZ, OF DES MOINES, IOWA.

INTERNAL-COMBUSTION ENGINE.

1,266,033.

Specification of Letters Patent. Patented May 14, 1918.

Application filed February 7, 1917. Serial No. 147,228.

To all whom it may concern:

Be it known that I, ANTHONY J. METZ, a citizen of the United States, and resident of Des Moines, in the county of Polk and State of Iowa, have invented a certain new and useful Internal-Combustion Engine, of which the following is a specification.

The object of my invention is to provide an engine of the internal combustion type.

10 More particularly it is my object to provide such an engine having the valves so arranged with relation to the cylinders as to facilitate the rapid intake of fuel and the rapid discharge of the exhaust gases.

15 A further object is to provide an engine of the kind mentioned, having the cam shafts arranged above the crank case and having parts so arranged that ready access may be had thereto.

20 A further object is to provide in such an engine suitable and efficient means for oiling the valve operating mechanism.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a side elevation of an engine embodying my invention, the upper portion of the casing wall being removed.

Fig. 2 shows an end elevation of the same, illustrating the arrangement of part of the hollow pipes.

Fig. 3 shows a transverse, vertical, sectional view through my improved engine.

Fig. 4 shows an enlarged, sectional, detail view of part of the engine shown in Fig. 3.

Fig. 5 shows a sectional view taken on the line 5—5 of Fig. 3.

Fig. 6 shows a sectional view taken on the line 6—6 of Fig. 4, and

Fig. 7 shows a vertical, sectional view through the oil pump.

I have illustrated in the accompanying drawings a four cylinder engine. In the illustration of my invention shown in the accompanying drawings, I have used the reference numeral 10 to indicate generally the crank case of the engine. At the upper end of the crank case 10, at the sides thereof, are overhanging flanges 11. Above the case are four cylinders 12, having at their

lower ends the flanges 13 resting on the flanges 11.

Between the successive cylinders are downwardly extending, transverse reinforcing 60 ribs 14. On each side of the cylinders is the water jacket 15.

In the cylinders are the pistons 16 pivoted to the piston rods 17, which piston rods are suitably connected with the crank 65 shaft 18.

Spaced laterally from the cylinders, on each side thereof, are removable casing members 19 which are bolted on the engine so as to be quickly and easily removed for allowing access to the valve operating mechanism hereinafter more fully described.

Above the cylinders is the engine head 20 having the water jacket members 21 and 22. Above each cylinder in the head is an open 75 space 23.

Arranged at the upper ends of the cylinders on opposite sides thereof, substantially at 45 degree angles with relation to the cylinders, are the brake valve stems 24 and 80 the exhaust valve stems 25, traveling in suitable bearings 26.

The open space 23 extends upwardly and laterally from each side of each cylinder, as clearly shown in Figs. 3 and 4. The space 85 23 in the lower wall of the engine head below the space 23 on each side of the cylinder is provided with two valve ports 27, above which are formed valve seats 28 for the valves 29. The valve ports 27 communicate on the intake side of the intake ports 30, and on the exhaust side of the exhaust ports 31.

There are two exhaust valves and two intake valves for each cylinder. Above one 95 intake valve for each cylinder a spark plug 32 is screwed into the engine head, and above the other intake valve of the same cylinder a plug 33 is screwed into the engine head in such a way as to be readily removable for permitting access to the valves.

Similarly above one exhaust valve of each cylinder there is a screw plug 33, and above the other exhaust valve of the same cylinder is a spark plug 32.

On the crank shaft 18 is a fly wheel 34 mounted in the casing 35. At the ends of the casing members 19 are the end casing walls 36.

Mounted in suitable bearings on opposite 110 sides of the cylinders 12 are hollow cam shafts 37 on which are cams 38. The cam

shafts 37 and the cams 38 are provided with openings 39 (see Fig. 6), leading from the interior of the shafts to the outer surfaces of the cams.

5 Located above each cam shaft 37 is a hollow shaft 40. On each shaft 40 is a sleeve 41 for each cylinder. Each sleeve 41 has a downwardly extending rocker arm 42 adapted to coact with one of the cams 38, and a pair of upwardly extending arms 43. The arms 43 on one side of the engine are connected with the respective valve stems 24 or 25, as the case may be.

10 On each valve stem is a collar 44, near its lower end, and between each collar 44 and the adjacent bearing 26 is a coil spring 45. The shafts 40 are hollow, and the shafts 40 and sleeves 41 are provided with openings 46 for admitting oil from the interior of the 15 shafts to the exterior thereof and to the sleeves.

15 Located within the casing wall 19 just below the engine head and adjacent to the valve stems 24 and 25 are oil pipes 47, having openings 48 adapted to discharge oil on the valve stems.

20 For supplying oil to the hollow shafts 37 and 40 and to the pipes 47, the following means has been provided:

25 30 Mounted just below and in communication with the oil chamber 10^a at the bottom of the crank case is an ordinary gear pump 49 having the gears 50 and 51. One of the gears 50 is mounted on a shaft 52 provided at one end with a flat upward projection 53 adapted to be received in a socket 54 in the lower end of the shaft 55. The shaft 55 is mounted in suitable bearings 56, and extends upwardly to position adjacent to one 35 of the cam shafts 37. On the upper end of the shaft 55 is a worm gear 58 in mesh with the worm 59 on said last mentioned cam shaft.

40 45 Leading from the pump 49 is an oil pipe 60 which leads upwardly on the outside of the crank case at one end thereof, and has near its upper end branch members 61. The hollow cam shafts 37 are rotatably mounted in the end walls 36. Covering the open ends 50 of the shafts 37 are suitable caps 62. The ends of the branch pipes 61 are screwed into the caps 62 so as to permit the flow of oil from the pipes 61 to the hollow shafts 37. It will be obvious that the shafts 37 rotate. 55 The shafts 40 which do not rotate, are supported by the walls 36 but do not extend through said walls.

60 65 Extending upwardly from the upper end of the pipe 60 is a pipe 63 having at its upper end branches 64, the ends of which are screwed into the walls 36 and communicate with the shafts 40, as shown in Fig. 6. Extending upwardly from the branch pipes 64 are pipes 65 which are 70 screwed into the walls 36 and communicate

75 with the respective oil pipes 47. In addition to being supported by the end walls 36, the shafts 40 are supported in bearings 66 formed on plates 67 secured to the walls of the water jackets 15. The walls of the water jackets 15 are provided with openings 68 for permitting the water to touch the plates 67 for assisting in cooling the shafts 40.

80 85 On the crank shaft 19 is a gear 69, shown by dotted lines in Fig. 3, in mesh with a suitably supported gear 70, shown by dotted lines in the same figure. On the cam shafts 37 are gears 71 which mesh with the gear 70. Meshing with one of the gears 71 is a magneto gear 72, shown by dotted lines in Fig. 3.

90 95 I will now describe the practical operation of my improved engine, with special reference to some of the new features thereof, and incidentally refer to some of the advantages of my new construction.

100 In the operation of my improved engine, it will be noted that the cam shafts are located above the crank case and are so arranged that by the removal of the casing members 19, ready access may be had to the cam shafts and also to the shafts 40 and the valve operating mechanism. This means that in an automobile of the ordinary type it is much easier to get at the valve operating mechanism than can be done with engines commonly in use.

105 110 Special attention is called to the operation of the oiling system of my engine. The pump takes the oil from the lower part of the gear casing and forces it to the shafts 37 and 40 and to the oil pipes 47. The oil passes into the shafts 37 and thence through the walls of said shafts and through the cams 38 for oiling the cam faces and also for oiling the faces on the arms 42 which engage the cam. Oil passes through the walls of the shafts 40 and through the sleeves 41, for oiling the rocker arms and the shafts 40. Oil is spurted from the pipes 47 upon the bearings 26 in which the valve stems travel, and will naturally flow downwardly to the lower end of said valve stem bearings for properly oiling the valve stems.

115 It will be noted also that the valve operating mechanism is extremely simple and direct.

120 125 One of the chief advantages of my improved engine lies in the location, arrangement and operation of the valves. It will be noted that the valve stems and the paths of travel of the valves are arranged at angles of substantially 45 degrees with relation to the plane in which the longitudinal axes of the cylinders lie. On account of this arrangement, it will be noted that the path of travel of the incoming fuel gases and the path of travel of the outgoing exhaust gases are direct, as indicated by the arrows in Fig. 4. Attention is also called in this con- 130

nection, to the fact that when the valves are raised they are not in the direct path of the incoming, and particularly they are not in the direct path of the outgoing, gases, so 5 that they become less heated than in ordinary forms of construction.

My engine is particularly devised as a high speed engine, and for such an engine the arrangement of the valves herein set 10 forth has an especial advantage. The exhaust gases travel almost in a straight line from the cylinders to the exhaust manifold, and the exhaust valves are so arranged as to be almost entirely out of the way of the 15 escaping exhaust gases. As a result, the exhaust gases may pass from the cylinder at a minimum speed.

Owing to the fact that the gases do pass 20 in a direct path rather than in a circuitous one from the cylinder, I have found it possible to, and do, time my intake valves so that they begin to open before the exhaust valves close, and this can be done without back pressure into the intake manifold. I 25 thus secure higher efficiency in my engine by affording a straight path for the discharge of the exhaust gases, and therefore avoid back pressure and reduce the friction 30 of the passing gases, and thereby permitting their freest escape, and at the same time increase the speed of my engine by permitting the exhaust gases to pass more quickly from the cylinder and by arranging the intake valves so that by the time the exhaust valves 35 are closed the intake valves are fully opened and the intake charge is well started on its way into the cylinder. I find that by arranging the exhaust valves as shown in Fig. 4, where they are largely out of the path 40 of the outgoing exhaust gases, the valves do not carbonize or collect carbon deposits as in many other engines. Any oil on the valve tends to drop toward the lower edge thereof, from which it is blown off by the 45 escaping gases.

The engine head may be quickly and easily removed for permitting access to the valves.

It may be mentioned in this connection 50 that owing to the ready passage of the exhaust gases away from the cylinder, there is less tendency for my engine to heat than where the exhaust gases are forced into a more circuitous path during their passage from the engine.

Attention is also called to the fact that I 55 have provided for each cylinder two intake ports controlled by valves, and two exhaust ports controlled by valves, for increasing the volume of gases which may be taken into 60 or discharged from the cylinder in a given time, and for increasing the speed with which the fuel may be fed to the cylinder or the exhaust gases discharged therefrom.

It will be noted that the valve stems are 65 arranged to travel at substantially 45 de-

gree angle with relation to the upright cylinder. This permits the insertion of the spark plugs and also the closure plugs 33 into the engine head in such a way as to permit ready access to the valves.

I have not attempted to give any exhaustive description of the operation of my engine nor of the advantages of its construction, but I may say in summary that three of the principal advantages of my construction lie in the location of the valve operating mechanism alongside the cylinders and above the crank case, whereby ready access to such mechanism may be had, and in the oiling system above described, and in the 75 location and arrangement of the valves.

Some changes may be made in the construction and arrangement of the various parts of my improved engine, without departing from the essential principles and 80 purposes of my invention, and it is my intention to cover by the patent to be issued hereon, any modified forms of structure or use of mechanical equivalents which may be reasonably included within the scope of my 85 claims.

I claim as my invention:

1. In an engine, an upright cylinder, a water jacket surrounding the sides of said cylinder, a removable head above said cylinder having a water jacket, casing members on opposite sides of said cylinder spaced from the water jacket, means for detachably connecting said casing members with said removable head, said head being formed to 95 leave a space above the cylinder, and being formed with passages from said space extending laterally, whereby exhaust gases from said cylinder may pass from the cylinder through said spaces and passages, by 100 making substantially a quarter turn, valve seats in said passages, valves adapted to contact with said seats having stems slidably mounted in said head, and means within the compartments formed by said casing members 105 for actuating said valves.

2. In an engine, an upright cylinder, a water jacket surrounding the sides of said cylinder, a removable head above said cylinder having a water jacket, casing members 115 on opposite sides of said cylinder spaced from the water jacket, means for detachably connecting said casing members with said removable head, said head being formed to leave a space above the cylinder, and being formed with passages from said space extending laterally, whereby exhaust gases from said cylinder may pass from the cylinder through said spaces and passages by 120 making substantially a quarter turn, valve seats in said passages, valves adapted to contact with said seats having stems slidably mounted in said head, and means within the compartments formed by said casing members 125 for actuating said valves, said means 130

comprising cam shafts, located near the lower portion of the cylinder, shafts, arms on said last described shafts, cams on said cam shafts, said arms being adapted to coact respectively with the cams and with the valve stems,

5. In an engine, an upright cylinder, a water jacket surrounding the sides of said cylinder, a removable head above said cylinder having a water jacket, casing members on opposite sides of said cylinder spaced from the water jacket, means for detachably connecting said casing members with said removable head, said head being formed to leave a space above the cylinder, and being formed with passages from said space extending laterally, whereby exhaust gases from said cylinder may pass from the cylinder through said spaces and passages, by making substantially a quarter turn.
10. In an engine, an upright cylinder, a water jacket surrounding the sides of said cylinder, a removable head above said cylinder having a water jacket, casing members on opposite sides of said cylinder spaced from the water jacket, means for detachably connecting said casing members with said removable head, said head being formed to leave a space above the cylinder, and being formed with passages from said space extending laterally, whereby exhaust gases from said cylinder may pass from the cylinder through said spaces and passages, by making substantially a quarter turn.
15. In an engine, an upright cylinder, a water jacket surrounding the sides of said cylinder, a removable head above said cylinder having a water jacket, casing members on opposite sides of said cylinder spaced from the water jacket, means for detachably connecting said casing members with said removable head, said head being formed to leave a space above the cylinder, and being formed with passages from said space extending laterally, whereby exhaust gases from said cylinder may pass from the cylinder through said spaces and passages, by making substantially a quarter turn.
20. In an engine, an upright cylinder, a water jacket surrounding the sides of said cylinder, a removable head above said cylinder having a water jacket, casing members on opposite sides of said cylinder spaced from the water jacket, means for detachably connecting said casing members with said removable head, said head being formed to leave a space above the cylinder, and being formed with passages from said space extending laterally, whereby exhaust gases from said cylinder may pass from the cylinder through said spaces and passages, by making substantially a quarter turn.
25. In an engine, an upright cylinder, a water jacket surrounding the sides of said cylinder, a removable head above said cylinder having a water jacket, casing members on opposite sides of said cylinder spaced from the water jacket, means for detachably connecting said casing members with said removable head, said head being formed to leave a space above the cylinder, and being formed with passages from said space extending laterally, whereby exhaust gases from said cylinder may pass from the cylinder through said spaces and passages, by making substantially a quarter turn.
30. In an engine, an upright cylinder, a water jacket surrounding the sides of said cylinder, a removable head above said cylinder having a water jacket, casing members on opposite sides of said cylinder spaced from the water jacket, means for detachably connecting said casing members with said removable head, said head being formed to leave a space above the cylinder, and being formed with passages from said space extending laterally, whereby exhaust gases from said cylinder may pass from the cylinder through said spaces and passages, by making substantially a quarter turn.

der through said spaces and passages, by making substantially a quarter turn, valve seats formed in said passages, and valves 35 adapted to coact with said seats.

5. In an engine, a cylinder, a crank shaft below the cylinder, a crank case therefor, a pair of valves adjacent to the upper end of said cylinder, valve operating mechanism 40 arranged alongside said cylinder above said crank case, including a cam shaft having a cam thereon, a third shaft, a sleeve on said third shaft, an arm on said sleeve arranged in operative relation with said cam, and a 45 pair of arms on said sleeve, connected respectively with said valves.

6. In a device of the class described, a plurality of engine cylinders, a crank shaft below the cylinders, a crank case therefor, compartments arranged alongside said cylinders above said crank shaft and crank case, pairs of valves arranged on opposite sides of each cylinder, adjacent to the upper end thereof, a valve operating mechanism in 50 each of said compartments, including a cam shaft having cams thereon, a rocker arm shaft, a sleeve on said rocker arm shaft for each cylinder, an arm on each sleeve, operatively connected with one of said cams, and 55 pairs of arms on each sleeve operatively connected with the adjacent pair of valves.

Des Moines, Iowa, January 25, 1917.
ANTHONY J. METZ.
